Inventor
A. H. Froom,

UNITED STATES PATENT OFFICE.

ACEL H. FROOM, OF SANTA MARIA, CALIFORNIA.

FOLDING CAMP KIT.

1,227,419.

Specification of Letters Patent. Patented May 22, 1917.

Application filed April 21, 1916. Serial No. 92,764.

To all whom it may concern:

Be it known that I, ACEL H. FROOM, a citizen of the United States, residing at Santa Maria, in the county of Santa Barbara, State of California, have invented certain new and useful Improvements in Folding Camp Kits; and I do hereby declare the following to be a full, clear, and exact description of the invention, such as will enable others skilled in the art to which it appertains to make and use the same.

This invention relates to improvements in camp kits and particularly to folding kits adapted to also contain food.

One object of the invention is to provide a folding receptacle which is particularly adapted for the use of automobilists when going on an extended trip to carry food and a camp kit, and which may be readily disposed on the running board of an automobile and which can be readily strapped to the back of a pack animal by exploring parties.

Another object is to provide a receptacle which can be opened and legs attached to provide a table.

Other objects and advantages will be apparent from the following description when taken in connection with the accompanying drawing.

In the drawing:

Figure 1 is a side elevation of my improved folding lunch box;

Fig. 2 is an end view;

Fig. 3 is a vertical section on the line 3—3 of Fig. 1;

Fig. 4 is a perspective view of the receptacle in position for packing or unpacking;

Fig. 5 is a perspective view of the receptacle showing the same set up as a table;

Fig. 6 is an enlarged vertical section on the line 6—6 of Fig. 2;

Fig. 7 is an enlarged vertical section on the line 7—7 of Fig. 2;

Fig. 8 is an enlarged vertical section on the line 8—8 of Fig. 6.

Referring particularly to the accompanying drawing, the kit comprises three sections 10, 11 and 12, the sections 10 and 11 being hingedly connected at 13 and the sections 11 and 12 hinged together at 14. Each of the sections has flanges 15 which abut the flanges of the other sections when the box is in folded position and are held in such position by the fastening devices 16.

The box when folded, has the general appearance of a large suit-case, and is provided with a handle 17, if desired, by means of which the device may be carried. In the outer corners of the sections 10 and 12 there are secured socket members 18 which are adapted to receive the detachable legs 19. Within the section 10 is a compartment 20 for holding the legs. Other camp kit articles can be placed in this compartment as desired, suitable clips 23 being provided for holding the axe 24 and clips 25 for other articles and tools. In the remaining compartment 21, the food is adapted to be stored. The sections 11 and 12 are provided with separable fastening devices or latches 22 for holding these sections in folded position, said latches being moved from without the kit by means of the buttons 22'. 75

Each of the socket members includes a hollow socket portion 26 with wings 27 extending from the two mutually adjacent outer sides. The corner edge portion at the meeting of these sides is thickened, as at 28 and kerfed vertically, as at 29, to provide the webs, between which webs and the said sides, the side plates of the sections fit. Within each socket member is secured a leaf spring 30, which bears against the leg when inserted therein, for the purpose of more effectively holding the leg. 80

When the device is to be used as a table the section 12 is swung down to permit the entire contents of the box to be removed, 90 as shown in Fig. 4. Then the fasteners between the sections 10 and 11 and 10 and 12 are released and all three of the sections inverted so that a table top will be formed. The latches 22 are, of course, engaged to hold the sections 11 and 12 immovable, then the device is inverted. The legs are then inserted in the socket members whereby a serviceable table top is produced. 95

From the foregoing it will be readily seen that I have provided an extremely simple and cheap lunch box and one which performs a dual function.

The box may be made of any suitable material, such as metal, wood, or other stiff and yet light material and can be made of convenient size to permit the same to be carried by the hand. 105

What is claimed is:

A combined lunch box and table includ- 110 ing hinged sections each comprising metallic side and top plates, grooved corner mem-

bers receiving the ends of the plates, certain of said corner members being formed with angular leg receiving sockets, and longitudinally extending leaf springs secured within said sockets and frictionally bearing against the legs to hold them within the sockets.

In testimony whereof, I affix my signature, in the presence of two witnesses.

ACEL H. FROOM.
